UNITED STATES PATENT OFFICE

145,054

DESIGN FOR AN EARRING

Marcel Boucher, New York, N. Y.

Application December 27, 1945, Serial No. 125,042

Term of patent 7 years

(Cl. D45—9)

To all whom it may concern:

Be it known that I, Marcel Boucher, a citizen of the United States, residing in New York city, in the county of New York and State of New York, have invented a new, original, and ornamental Design for an Earring, of which the following is a specification, reference being had to the accompanying drawing, forming part thereof.

Fig. 1 is a front elevational view of an earring, and

Fig. 2 is the side view thereof.

I claim:

The ornamental design for an earring, substantially as shown.

MARCEL BOUCHER.
